CLAIM

I claim the ornamental design for a garment hanger, as shown and described.

DESCRIPTION

FIG. 1 is a front perspective view of a garment hanger in accordance with the new design;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

The claimed design is not limited to the gray color shown in the drawings.
